GOVERNOR FOR TUBE CLEANER MOTORS

Paul E. Good, Riverton, N. J.

Application June 5, 1937, Serial No. 146,673

7 Claims. (Cl. 121—34)

This invention relates to tube cleaner motors, and more particularly to a means for governing such motors.

Tube cleaners as employed in the removal of scale from boiler tubes necessarily involve the use of a motor of extremely small size and, accordingly, offer extreme difficulty in the provision of governing mechanism for controlling the speed of operation; so much so, in fact, that despite the fact that governing of the speed is substantially essential, no present-day tube cleaner has been governor-equipped, the sole method of speed control being either through manual control of the fluid delivered to the motor or by crowding or retarding the rate of feed of the motor through the tube so that the scale, acted upon by the motor driven cleaning elements, itself acts as a brake to keep the operation of the motor within reasonable speed limits. Obviously, either method is unsatisfactory, for manual throttling of a supply to a hose which is being hand fed through a tube, means that the control valve must be located at the end of the tube and, accordingly, presents difficulties as to accessibility. Furthermore, since the operator has no way of knowing the rate of scale variation through a given tube, he is only warned of excessively speeded up or retarded action on the part of the motor through transmitted sound. The delay in effecting a control may cause serious injury to the tube before the speed can be properly regulated. The irregularity of the scale, obviously, also presents difficulty in control of the speed of the motor through controlling the speed of feed of the cleaner through the tube since a heavy patch of scale may be immediately succeeded by a light patch, or vice versa, with the result that the motor suddenly speeds up, or is suddenly retarded or even stopped. The difficulties arising from the conditions just recited are accentuated by the fact that the motor is necessarily small, and because of its type makes excessive demands upon its air supply necessitating large ports.

In addition to the damage caused to the motor or tube by the uncontrolled action of the motor, such action is in many cases extremely dangerous. The cleaners employed on the motor are flexibly coupled to the motor so that they may be moved radially of the tube, and obviously, if through carelessness, as often happens, the cleaner is projected from the far end of the tube, there is no resistance to the pivotal swing of the cleaner elements which spread radially causing considerable damage in their own vicinity and in

many cases breaking from their moorings and injuring workmen at a distance.

The principal reason why such motors have not been equipped with governors has been the absence of a compact governor construction which lends itself to use in the motor. Since such motors must be of short length to enable their passage about curves in the tubes being cleaned, any material increase in the length thereof will, obviously, result in a decrease in usefulness since, with the increased length the motor becomes unuseable in tubes having bends of certain radius. Accordingly, the primary objects of this invention are the production of a governor-construction which may be very readily adapted to the present-day tube cleaning motors without materially varying the construction thereof or adding to their length, which may be very cheaply manufactured and readily assembled, and which at the same time will be sufficiently accurate in its operation to insure maintenance of the motor speed within given predetermined limits.

These and other objects I attain by the construction shown in the accompanying drawings wherein, for the purpose of illustration I have shown a preferred embodiment of my invention and wherein:

Fig. 1 is a perspective view showing a tube cleaner motor constructed in accordance with my invention;

Fig. 2 is a longitudinal sectional view through a preferred form of the motor;

Figs. 3, 4 and 5 are sections on lines 3—3, 4—4, and 5—5 respectively of Fig. 2;

Fig. 6 is a side elevation of the motor shaft;

Fig. 7 is an end elevation thereof illustrating the governor-mounting;

Fig. 8 is a side elevation of the removable portion combining with the head to mount the governor valves;

Fig. 9 is a combined perspective of the sections of the governor valve;

Fig. 10 is a detail sectional view through the valve;

Fig. 11 is a fragmentary sectional view showing a modified form of the invention;

Fig. 12 is a side elevation of a portion of the motor shaft showing the governor-construction of Fig. 11;

Figs. 13 and 14 are sections on lines 13—13 and 14—14 respectively of Fig. 11;

Fig. 15 is a section on line 15—15 of Fig. 14;

Fig. 16 is a fragmentary sectional view of a further modified form of the invention;

Fig. 17 is a detail view of the governor end of the shaft in the form of the invention shown in Fig. 16;

Figs. 18 and 19 are sections on lines 18—18 and 19—19 respectively of Fig. 16;

Fig. 20 is an elevation of the shaft head in the form of the invention shown in Figs. 16 to 19; and

Figs. 21 and 22 are combined views showing 10 different sets of springs which can be employed in the form of invention shown in Figs. 1 to 15 in order to secure graduated port closing in the governor mechanism.

Referring now more particularly to the drawings, the numeral 10 generally designates a casting divided by a partition into motor and inlet chambers 11 and 12. The motor at present illustrated is of the sliding vane type, comprising an eccentrically disposed cylinder 13 the wall of 20 which is formed with intake and exhaust ports 14 and 15, of which the intake ports are surrounded exteriorly of the cylinder by an inlet conduit 16. The exhaust ports communicate with passages 17 formed in the cylinder casting 25 which passages are maintained in alignment with openings in a thrust-washer 18 and the forward end of the casing by a dowel 19. The rotor-body 20 in the cylinder has the usual sliding vanes 21 provided in this type of motor, and, at its forward end, has an extension 22 projecting through thrust washer 18 and a bushing 23 carried by the casing to the exterior of the casing at which point it is provided with a suitable connecting means 24 for an operating head 25. At its rear end, the rotor body 20 is provided with an extension 26 projecting through a split thrust-washer 27 and bushing 28, the latter being held in position through a threaded locking ring 29. The split washer 27 and bushing 28 are held against 40 rotary movement with relation to the cylinder by the hereinbefore mentioned dowel 19, and are provided with aligned openings registering with inlet conduit 16, that of the bushing being indicated at 30 in Fig. 4. The structure so far described is common to all forms of the invention herein illustrated.

Outwardly of the bushing, the shaft extension 26 is provided with an enlarged head 31 bearing against bushing 28. A head of this character is 50 provided in the usual structures and is, in accordance with my invention, slightly modified to incorporate the governor-structure. In the form at present under discussion, an extension 32 for the head is secured to the head by bolts 33 threading into openings 34 of the head. This extension has a substantial sealing engagement at 35 with a thimble 36 inserted in the inner end closure 37 of casing 10 and surrounding the air inlet opening 38 of such closure. The extension 55 32 and head 31 are provided with semi-circular seats 39 receiving valve casings 40. Valve casings 40 are each in the form of a thimble, the outer end of which is closed and the inner end of which is in communication with the compartment defined by the valve casings, head, and extension 60 32, and the head is provided with a conical extension 41 which will direct air entering through inlet 38 into the inner ends of these casings. The ports 42 of the valve casings open to the 65 compartment at the exterior of the head and, accordingly, are in communication through the ports of bushing 28 and washer 27 with the inlet 16 of the motor cylinder. These ports are controlled by valves 43 each comprising upper and 70 lower ring elements 44 connected by radial ribs 75

45. At the inner end of the valve the radial ribs join at their centers and provide a seat 46 for a spring 47 the opposite end of which engages in a socket 48 formed in the outer wall of the valve casing. Inward movement of the valves is limited through engagement with the seats for the valve casing.

It will be obvious that by properly proportioning the strengths of spring 47 and the weight of valve 43 these valves can be caused to move 10 radially under centrifugal force to close the ports 42 when a predetermined rotor speed is attained by rotor 20.

Obviously, a construction of this type may be incorporated, while utilizing very slightly more 15 than the waste space ordinarily provided between the inner end of head 31 and the enclosure member 37, in the usual tube cleaner motor construction, and a governor of the type shown will be sufficiently accurate to maintain the speed of the 20 motor within a safe operating range. Obviously, under these circumstances it likewise becomes possible to utilize higher pressures, thus eliminating stalling of the motor under what would normally be overload conditions where the pressures 25 utilized must be kept low enough to insure against damaging operation in event the conditions become such as have been hereinbefore pointed out.

In the form shown in Figs. 11 to 15, the head 30 31a is provided with a tubular extension 49 the outer end of which is provided with a flange 50 having sliding engagement with the thimble 36. The tubular extension 49 has radial slots 51 which are controlled by sleeve valve 52 mounted 35 for oscillation about the tubular extension 49 and having ports 53 for registration with slots 51 of the extension.

Within the inlet compartment formed by the extension 49 and head 31a is a pair of bell crank 40 weight arms 54, the lighter arms 55 of which project through slots 56 in the extension 49 and are provided with rounded heads engaging in openings 57 formed in the sleeve valve 52. Radial movement of the heavier arms is opposed 45 by springs 58, and the arrangement of the parts is preferably such that, assuming the direction of rotation of the motor to be that illustrated by the arrow in Fig. 14, the outward radial movement of the heavier arms will cause a shifting 50 of the sleeve in opposition to the direction of movement of the arrow, thus taking advantage of the inertia of sleeve 52 to assist in positioning the valve, particularly under sudden increases in speed. This structure is particularly advantageous 55 in that it insures a rapid cut-off of the pressure supply at such sudden increases of speed, thus preventing dangerously rapid rotation of the motor when extremely light scale is encountered, or the motor is accidentally projected from the far end of a tube being cleaned.

The pivots for the bell crank arms 54 comprise pins 59, cottered, or otherwise secured against longitudinal movement with relation to the head, as indicated at 60. These pins serve at their inner ends as a mounting for a cone-shaped projection 61 which serves the dual function of deflecting the incoming air toward the governor ports and to prevent the incoming blast of air from exerting flow head-pressure on the governor-weights, which would tend to impede the operation thereof by causing excessive frictional engagement with the head.

In the form of invention shown in Figs. 16 to 20, the head 31b has a pair of outwardly pro- 70

jecting arms 62, the outer ends of which are connected by a cross bar 63, the purpose of which will presently appear. The outer surfaces of these arms are curved upon a common radius coaxial with the axis of the extension 26 and fittingly receive the inner end of a sleeve 64 the outer end of which is flanged to sealingly engage the thimble 38. This sleeve is provided with radial slots 65 and upon its exterior has mounted a sleeve valve 66 which is similarly slotted as indicated at 67. The arms 62 have openings 68 mounting pins 69 which, in turn, mount bell crank weight arms 70 the heavier arms 71 of which are directed longitudinally of the compartment formed by the head and sleeve and are normally urged inwardly through the medium of governor springs 72. The lighter arms project through slots 73 formed in the sleeve 64 and have rounded heads engaging in openings 74 in the sleeve valve 66. In this form the sleeve valve is, upon outward movement of the weight arms 71, shifted longitudinally upon sleeve 64 to close the ports 65. In order to direct the air outwardly to these slots as in the previous constructions, and to prevent interference for the blast of incoming air with the governor arms, the outer ends 75 of arms 62 are formed as fragmentary surfaces of a common cone. The connecting arm 63 is inset slightly from the outer extremity of the arms, as more clearly shown in Fig. 20, and a curved shielding plate 76 bridges the gap between the arms and has its ends engaged in slots 77 formed in the sleeve. Such plate substantially completes the conic surface partially defined by the ends 75 of the arms.

In addition to the graduated closing afforded by radial movement of valves of the same weight opposed by springs of the same strength as suggested in the form shown in Figs. 1 to 15, the graduation as to effective port area can be further controlled by making the springs of different characteristics. This may be either by making all of the springs of the valve units of different characteristics, as shown at 47a, 47b, 47c, and 47d in Fig. 21, or by arranging the valve units in groups, each group being controlled by springs of the same characteristics, as indicated at 47e and 47f in Fig. 2. While, for the sake of illustration, I have shown the springs themselves as employed to control the closing time, and such structure is obviously mechanically preferable, this end may likewise be accomplished by varying the weight of the valve unit proper.

As will be noted from the illustration, the port area provided by the various centrifugally controlled valves is at least equal to, if not in excess of, that provided in the motor supply duct 30, with the result that the motor has a full supply upon maximum demand, while at the same time the governor has control of the motor at any time that it may arrive at an excessive speed. These conditions are met by providing the motor shaft with the enlarged heads present in each of the forms illustrated so that an increased area for port formation is afforded.

It will be understood that while I have referred to engagement with the thimble 38 as being a sealing engagement, this engagement need only be such as to substantially seal the joinder between the thimble and head since a slight leakage would be in no way critical. It will also be understood that the several modi-

fications hereinbefore illustrated are merely specific examples of my invention and I, accordingly, do not wish to be understood as limiting myself to the constructions herein described except as hereinafter claimed.

I claim:

1. The combination with a high speed tube cleaner motor comprising a cylindrical casing of small diameter, means dividing the casing into supply and motor chambers having port communication with one another, a rotary motor in the motor chamber including a cylinder having a large supply port in communication with the supply chamber, a rotor shaft projecting into the supply chamber and an enlarged head on the shaft within the supply chamber, the supply chamber having an axial inlet port, of an annular means on said head having substantial sealing engagement with the peripheral wall of the inlet port and dividing said supply chamber into primary and secondary compartments of which the secondary compartment is in constant communication with the supply port of the motor chamber, said annular means having ports to place said compartments in communication with one another, said ports being arranged on an approximate diameter considerably in excess of the diameter of the shaft and having a combined maximum area at least as great as the supply port of the cylinder, and centrifugally controlled means carried by the head and first-named means for controlling the area of said ports.

2. A device as claimed in claim 1 wherein the centrifugally controlled means comprises radially movable valves.

3. A device as claimed in claim 1 in which the means on the head comprises a longitudinally slotted sleeve and the centrifugally controlled means comprises a valve rotatable on said sleeve.

4. A device as claimed in claim 1 wherein the means on the head comprises a circumferentially slotted sleeve and the centrifugally controlled means comprises a longitudinally movable sleeve valve mounted on said sleeve.

5. A device as claimed in claim 1 in which the centrifugally controlled means comprises a plurality of radially extending valve casings each having a spring-opposed radially movable valve therein, said valve casings having their inner ends opening to the primary compartment and having ports controlled by the associated valve opening into the secondary compartment.

6. A device as claimed in claim 1 in which the centrifugally controlled means comprises a longitudinally slotted sleeve secured to and rotating with the head, a second longitudinally slotted sleeve oscillatable about the first-mentioned sleeve, means normally holding said sleeves with the slots thereof in alignment and centrifugally controlled means to shift said second sleeve and move said slots out of alignment at predetermined rotative speeds of said head.

7. A device as claimed in claim 1 wherein the centrifugally controlled means comprises a circumferentially slotted sleeve secured to and rotating with said head, a longitudinally slidable sleeve mounted upon the first-named sleeve and likewise having circumferential slots, and centrifugally controlled means for longitudinally moving the last-named sleeve.
